UNITED STATES PATENT OFFICE.

WESTERN UNDERWOOD, OF SANTA MONICA, CALIFORNIA, ASSIGNOR TO WESTINGHOUSE ELECTRIC & MANUFACTURING COMPANY, A CORPORATION OF PENNSYLVANIA.

DESIGN FOR A LIGHTING STANDARD.

Application filed October 23, 1925. Serial No. 15,233. Term of patent 7 years.

To all whom it may concern:

Be it known that I, WESTERN UNDERWOOD, a citizen of the United States, residing at Santa Monica, in the county of Los Angeles and the State of California, have invented a certain new, original, and ornamental Design for Lighting Standards, of which the following is a specification, reference being had to the accompanying drawing, forming a part hereof.

Figure 1 is an elevational view of my new design of lighting standard.

Figure 2 is an enlarged detail view of the lower portion of my lighting standard, the

upper portion thereof being broken away, and

Figure 3 is an enlarged view of the central and upper portions of my lighting standard, the lower portion and a part of the upper portion being broken away.

I claim:

The ornamental design for a lighting standard as shown.

In testimony whereof, I have hereunto subscribed my name this 6th day of Oct., 1925.

WESTERN UNDERWOOD.
